Application November 6, 1943, Serial No. 509,262

19 Claims. (Cl. 250—36)

1

The present invention relates to the art including automatic frequency control systems, especially for ultra high frequency oscillators of the thermally-tuned "Klystron" type. In such oscillators a frequency-determining element in the form of a cavity resonator is tuned to determine the output frequency. The resonator tuning means comprises a thermally expansible strut or element which varies the resonator tuning upon expansion or contraction thereof. This expansion is caused by the application of electrical power to the strut, either by electrical conduction through the strut or by application to a heating coil in close contact with the strut.

The present invention is more particularly directed toward improved circuits and apparatus for controlling the application of this electrical power to effect the expansion of the tuning strut. For this purpose a control signal is produced corresponding to deviation of the output frequency of the resonator from a desired value. This control signal then controls the application of electric power to the thermal tuning control element or strut to restore the oscillator to its desired frequency value by returning one or more resonators thereof.

Such electrical power is preferably of the alternating type in order to gain ease of control and amplification and to produce a minimum of undesired interaction between the applied power and the electron beam of the oscillator, due to the inherent magnetic fields associated with such electric power. For this reason the power frequency utilized is preferably of a value higher than any modulation frequency which it is desired to apply to the oscillator or which is utilized in the system, and also sufficiently high so that the inherent thermal inertia of the expansible tuning control element will prevent any fluctuation in the extension of this control member in response to the alternation of the applied power.

Accordingly, it is an object of the present invention to provide improved frequency control apparatus for ultra high frequency oscillators, especially but not necessarily of the thermally tuned type.

It is another object of the present invention to provide an improved automatic frequency control system for thermally tuned ultra high frequency oscillators by controlling the application of electrical power to the thermal tuning element of such oscillators.

It is a further object of the present invention to provide improved apparatus for controlling the application of electrical heating energy to a ther-

2

mally-responsive tuning element in an ultra high frequency oscillator to control the frequency thereof.

It is another object of the present invention to maintain an ultra high frequency thermally tuned oscillator in a desired frequency condition by control of the application of alternating electrical power to the thermal tuning control element of this oscillator.

10 Other objects and advantages of the present invention will become apparent from the specification and drawings, wherein

Fig. 1 shows a schematic block diagram of a system in which the present invention may be utilized;

Referring to Fig. 1, there is shown one form of system in which the present system may be utilized. This figure illustrates a superheterodyne receiving system in which a received wave excites a receiving antenna 11 connected to a mixer 12. A local oscillator 13 supplies its output wave to the mixer 12, which thereupon produces a difference or intermediate frequency having the same 40 modulation as the wave received by antenna 11. This intermediate frequency is amplified by a suitable amplifier 14 whose output is connected to any desired type of utilization circuit 15. Amplifier 14 is generally of the tuned type to provide suitable selectivity for the received wave, and, accordingly, it is desirable to maintain the 45 output frequency of oscillator 13 in fixed relation to the frequency of the wave received by antenna 11 and differing therefrom by an amount equal

50 to the tuned intermediate frequency of amplifier 55

14. For this purpose the output of amplifier 14 is supplied to a discriminator 16 which is adapted to produce an output control signal having a polarity corresponding to the sense of deviation of the actual intermediate frequency from the desired value of this frequency, and also having a magnitude corresponding to the magnitude of this deviation. This output control signal of discriminator 16 then actuates a tuning control circuit 17, which is adapted to readjust the output frequency of oscillator 13 to the value producing the desired intermediate frequency.

It will be understood that in place of the receiving antenna 11, there may be connected any suitable source of reference frequency with respect to which it is desired to maintain the output frequency of oscillator 13 in predetermined frequency relation, such as having fixed frequency difference with regard thereto. Alternatively, oscillator 13 may be connected directly to a suitable ultra-high-frequency discriminator functionally equivalent to discriminator 16.

Fig. 2 shows one form of discriminator 16 in association with a tuning control circuit 17 according to the present invention, for controlling an oscillator 13. Oscillator 13 is shown as being of the thermally tuned "Reflex Klystron" type, although it may be of any high frequency type, preferably thermally tuned. "Reflex Klystron" oscillators are illustrated in Fig. 2 of Varian and Hansen Patent No. 2,250,511, issued July 29, 1941, and carry R. M. A. designations such as 2K37, 2K39, and 2K21.

Oscillator 13 is illustrated as comprising a grounded resonator 21 having a pair of electron-permeable grids defining a gap 22 through which an electron beam from a cathode 23 is projected by means of a battery 24 connected between cathode 23 and the grounded resonator 21. The electron beam passing through resonator 21 is reversed and reflected by a reflector electrode 25 which is maintained at a suitable slight voltage difference with respect to cathode 23 by means of its connection to a variable tap 26 on battery 24. The output frequency of oscillator 13 may be controlled or adjusted by adjusting the resonant frequency of resonator 21. This may be done by distorting one wall of the resonator 21, which may be made flexible for this purpose, as shown at 20, so as to adjust gap 22. Such adjustment may be effected by means of a tuning control strut member schematically illustrated at 27, whose expansion and contraction is controlled by electric power supplied thereto. In the present instance, such electric power is illustrated as applied to the center of strut 27 by means of a connection 28, the ends of strut 27 being grounded by means of their abutting connection to flanges on resonator 21. In this way electric current may be made to flow in the two halves of strut 27. Such current flow produces internal heating of the strut, which thereupon expands and varies the spacing of resonator 21. This expansion may be opposed by means of suitable springs (not shown) and atmospheric pressure on the evacuated resonator, which serve to return the resonator to its original position upon contraction of strut 27 following decrease of its heating excitation. It is to be understood that other types of oscillators of the thermally tuned type may be used in place of oscillator 13 wherever desired.

The present invention is directed especially toward the provision of improved control circuits for controlling the energization of strut 27. In

order to derive a control signal for controlling the strut excitation, the output of intermediate frequency amplifier 14 is supplied to a discriminator 16 of conventional type which is adapted to produce an output control voltage between its output lead 31 and grounded lead 30 of a magnitude proportional to the magnitude of the frequency deviation of the intermediate frequency from the value to which the discriminator 16 is tuned, this output voltage having a polarity corresponding to the sense of this frequency deviation. That is, for intermediate frequencies below the desired value, a positive output voltage is derived from discriminator 16; for intermediate frequencies above the desired value, a negative output voltage is produced.

According to the present invention, this discriminator output control signal controls the application of alternating power from a source 32 to the strut 27. Source 32 is connected to a transformer 33 having a voltage divider 34 connected across the secondary thereof. The movable tap 35 of the voltage divider 34 is grounded. One end, illustrated as the left end in Fig. 2, of the transformer secondary is connected through a blocking condenser 36 and a load resistor 37 to the anode of a control tube 38. The grid of control tube 38 is connected directly to output lead 31 of discriminator 16. The cathode of the tube 38 is connected to ground through a biasing resistor 39 having a by-pass condenser 41. The anode of tube 38 is connected through the resistor 37 and a further resistor 42 to a source 43 of positive anode voltage. Source 43 may be bypassed to ground through a by-pass condenser 44 so as to maintain substantially constant unidirectional potential. The anode of tube 38 is connected through a coupling and blocking condenser 45 and a grid input resistor 46 to the control grid of a power amplifier tube 47. The second end of the secondary winding of transformer 33 is also connected to the grid of amplifier 47 through a blocking condenser 48. It will be seen that condensers 36 and 48 prevent the grounding of the anode of tube 38 or the grid of amplifier 47 by virtue of the ground connection of tap 35 of voltage divider 34.

Tube 38 acts effectively as a variable resistance under the control of the voltage applied to its grid by lead 31. The equivalent circuit of this tube is shown in Fig. 3, where the variable resistance 38' represents the resistance of the tube 38. This variable resistance 38' is connected in series with the resistance 37 across source 32' which represents the voltage developed across that portion of resistor 34 between the left end of the secondary winding of transformer 33 and the grounded variable tap 35. In this way the alternating potential of point 40, corresponding to the anode potential of tube 38, may be varied by variation in the resistance 38' under the control of the discriminator output voltage.

This alternating potential is combined with a second alternating potential derived from source 32'' which represents the voltage developed across that portion of resistor 34 between the grounded tap 35 and the right end of the secondary of the transformer 33 of Fig. 2. As is indicated in Fig. 3, the alternating voltage of source 32' is connected in phase opposition to that of source 32''. The reason for this may be seen from the following considerations. The actual variation in resistance of tube 38 under the control of the discriminator output voltage is relatively small,

producing only a small variation in the alternating potential of point 40. For example, the potential at point 40 may vary between 100 and 110 volts. The proportional or percentage variation of this alternating potential may be increased by subtracting a fixed amount from this variable voltage. For example, if the source 32' has a voltage of 90 volts, the resultant voltage applied to the input of tube 47 of Fig. 1 will vary between 10 and 20 volts, representing a much greater proportional change. Also, in this way, the average voltage obtained is lowered to a more suitable value, which, as will be seen, determines the normal oscillator frequency. The difference between the variable voltage derived from source 32' and the fixed voltage derived from the source 32'' is amplified in the power amplifier 47, whose output is coupled to the tuning strut 27 by a suitable power transformer 49, and thereby serves to correspondingly control the tuning of oscillator 13.

In operation, with zero output from discriminator 16, the variable tap 35 is adjusted to a point such that the alternating power applied to strut 27 is of the proper value to produce an oscillator output frequency which differs from the received wave or reference frequency by the desired intermediate frequency. Thereafter, any variation in the relation between the reference frequency and the oscillator frequency will produce a corresponding signal output from discriminator 13. This output signal will correspondingly increase or decrease the effective resistance of tube 38 so that the alternating voltage applied to amplifier 47 will correspondingly increase or decrease, providing a corresponding change in the power applied to the tuning strut and returning the oscillator to provide a new oscillator frequency which has the desired relation to the reference frequency. In this manner the frequency of oscillator 13 is maintained in substantially fixed relation to the reference frequency supplied to the mixer 12. Variable tap 35 will therefore be seen to provide means for setting the datum of the system which will be maintained by the control action of the control circuit utilized.

Fig. 4 shows a system similar to Fig. 2 in which a slightly different connection for the source 32 is utilized. In this figure the positive potential source 43 is connected to the variable tap 35 of the voltage divider 34 connected across the secondary of the transformer 33 energized from source 32. The by-pass condenser 44 effectively grounds tap 35 with respect to alternating potentials, so that the circuit of Fig. 4 operates in the same manner as that of Fig. 2. Blocking condenser 48 now serves to isolate the grid of tube 47 from the high positive potential of source 43. The blocking condenser 36 and the isolating resistor 42 of Fig. 2 are no longer necessary.

In Fig. 5 the variable resistance provided by tube 38 is connected in series with an adjustable resistance in the cathode circuit of tube 38. Thus, a variable resistor 51 is provided connected between a positive source (which may be the same as source 43) and the cathode of tube 38, which is connected to ground by an adjustable resistor 52 having an adjustable tap 53. In this manner the resistor 52 is in series with the variable resistance provided by tube 38. The discriminator output is connected between the grid of tube 38 and ground, as by terminals 54. Source 32 now energizes the circuit by the con-

nexion of the secondary of transformer 33 in series between the anode of tube 38 and positive source 43. By-pass condenser 44 again serves to connect the secondary of transformer 33 to ground.

It will be seen that with a zero signal applied to the grid of tube 38 from the discriminator, the bias provided by the action of resistors 51 and 52 serving as a voltage divider will cause a pre-determined alternating voltage to appear across resistor 52, through the action of tube 38 as a cathode follower device. This voltage may be adjusted by suitable adjustment of tap 53 and is then utilized to energize the tuning strut in the manner to be described below, to provide the normal and desired oscillator frequency. Upon the appearance of a signal from the discriminator, the bias on the grid of tube 38 is correspondingly changed, producing a change in its plate resistance and a corresponding change in the alternating voltage component appearing across resistor 52. The relationship between the distributor signal impressed on the grid of tube 38 and the resulting change in alternating voltage produced can be adjusted by adjusting the resistance 51 to adjust the bias acting on grid 38.

To utilize this voltage component to control the tuning strut, the primary of a voltage transformer 55 is connected to the cathode of tube 38 through a blocking condenser 56 and is also connected at its other terminal to ground. In this way the alternating component of voltage across resistor 52 is impressed across the primary of transformer 55, while any direct current flow is blocked by condenser 56. The secondary of transformer 55 is center-tapped and is connected to a push-pull power amplifier stage comprising tubes 47' and 47'' which have the same function as the power tube 47 of the prior circuits. The output of amplifier 47', 47'' is connected to the tuning strut through a power transformer 49'. This circuit thus operates in similar fashion to the prior-described circuits.

Fig. 6 shows a further refinement on the circuit of Fig. 5. Thus, the control tube is shown as a double triode 38'. The first section of this double triode 38', comprising anode 56, grid 57 and cathode 58, is connected in a manner similar to tube 38 in Fig. 5; that is, the secondary of transformer 33 which is energized from source 32 is connected between positive source 43 and anode 56. Source 43 is also by-passed to ground by condenser 44. Cathode 58 is again connected to a voltage divider 51, 52 which serves to provide bias for the grid 57 and as a cathode follower resistor. One of the input terminals 54 is connected to grid 57 through a resistor 59. A condenser 61 is connected between grid 57 and cathode 58. The other of input terminals 54 is supplied with a suitable potential from a second voltage divider 60 which may also be energized from source 43 or any other source of positive unidirectional potential.

This first section of tube 38' operates in essentially the same manner as does Fig. 5. The voltage divider 60 merely permits the bias on grid 57 to be set independently of the adjustment of resistor 51 forming part of the voltage divider 51, 52. In this way a voltage is developed across adjustable resistor 52 in the same manner in Fig. 5. Resistor 59 and condenser 61 serve to filter out any transient pulses which may appear in this discriminator output and supply a slight amount of delay in the response of the control

circuit to the output signal so that operation of the control circuit is smoothed.

The second section of the double tube 38', comprising anode 62, control grid 63, and cathode 64, serves as an amplifier for the voltage appearing across resistor 52. Thus, it will be clear that this voltage is also impressed between grid 63 and cathode 64, and therefore will be amplified by the second section of tube 38'. The operating bias of grid 63 may be independently adjusted by the adjustable tap 65 on voltage divider 60. The output of this second section then energizes the input transformer 55 for the push-pull amplifier 47', 47'' and thereby energizes the tuning strut 21 of the oscillator 13.

Fig. 7 shows a circuit similar to that of Fig. 6, in which a greatly increased amplification may be obtained. In the circuit of Fig. 7 the grid 63 of the second section of double triode 38' is connected directly to grid 57 instead of having a fixed bias. Thus, when, for example, the discriminator output becomes positive, producing a decreased resistance for the first section of tube 38' and increasing the voltage across resistor 52, this same positive potential is applied to grid 63, further increasing its amplification of the voltage across resistor 52. In this way much higher amplifications of the strut controlling voltage are obtained for large frequency deviations, permitting the circuit to operate more quickly to restore the oscillator frequency to its proper value when the relationship between oscillator and reference frequencies has changed. The amplified output of the second section of tube 38' is supplied to the transformer 55 and the push-pull amplifier 47', 47'' to energize the tuning strut.

It will be clear that in Figs. 5, 6 or 7 a single power amplifier such as 47 of Figs. 2 or 4 may be utilized, and, conversely, a push-pull amplifier of the type shown in Figs. 5, 6 or 7 may be utilized in Fig. 2 or 4.

Each of the preceding circuits has derived the alternating strut energizing voltage through what is essentially variable voltage divider action. In Fig. 8, however, the discriminator output is utilized to modify the amplification of an alternating voltage and thus provide a variable alternating voltage for use in energizing the strut.

In Fig. 8 the discriminator output is impressed on a control grid 71 of a double triode 72 similar to tube 38'. The anode 73 of tube 72 is connected directly to the positive source 43. Cathode 74 is connected to ground through a cathode follower resistance 75 by-passed by condenser 76. The grid 77 of the second section of tube 74 is energized by an alternating voltage from source 32 which is made adjustable by voltage divider 78. Cathode 79 is connected to cathode 74, and anode 81 is connected through the primary of transformer 55 to the positive voltage source 43. Transformer 55 then energizes the power amplifier feeding the tuning strut.

In operation, assuming for the moment zero discriminator output, the normal or zero-input current passing through the first section of tube 72 produces a predetermined voltage across resistor 75 which provides the bias for grid 77. This voltage and the alternating voltage impressed on grid 77 are adjusted to provide the excitation for the tuning strut necessary for the desired normal operating frequency of oscillator 13.

A positive potential derived from the discrimi-

nator and impressed on the grid 71 will increase the drop across resistor 75 and will thereby decrease the excitation of the tuning strut. Correspondingly, a negative output from the discriminator will decrease the voltage across resistor 75 and will increase the amplification of the alternating voltage impressed on grid 77, thereby producing greater tuning strut excitation. By a proper choice of the polarity of the discriminator output relative to the desired change in oscillator voltage, this action will serve to maintain the oscillator frequency at the desired value. Voltage divider 78 may be adjusted and provides a manual tuning control for the oscillator frequency just as in the preceding figures.

Fig. 9 shows a more complete circuit diagram for the present invention operating in a fashion similar to that of Fig. 8. In this figure, source 32 and transformer 33 are connected to a bridge network, comprising a voltage divider 81 having a grounded adjustable tap 82, and a pair of equal resistances 83, 84. Resistor 83 may be provided with an adjustable tap 85 connected to the grid of power amplifier 86 similar to tube 47 of the prior circuits. Blocking condensers 87 and 88 are inserted in the circuit for direct current isolation but have no effect upon the alternating current bridge. By proper adjustment of the tap 82, zero alternating voltage will appear between the junction 91 of resistors 83, 84 and ground. Junction 91 is then supplied with a unidirectional voltage which provides the bias for tube 86 and controls the amplification of the alternating voltage impressed upon the grid of tube 86 by means of tap 85. Junction 91 is connected through an isolating resistor 92 to a single-pole, double throw switch 93, which is adapted to render the automatic frequency control system operative or inoperative.

In the "on" position of switch 93, a potential is impressed at junction 91 which is controlled by the discriminator 16. As shown in Fig. 9, one terminal 31 of discriminator 16 is connected directly to switch 93. The other terminal 30 of discriminator 16 is connected through a resistor 94 to a source of negative potential 95. A by-pass condenser 96 is connected between this latter terminal 30 and ground to by-pass all alternating current components. Also connected to this terminal 30 is the cathode 97 of a control tube 98 whose anode 99 is grounded. The grid 101 of control tube 98 is connected to the junction 102 of a resistor 103 and condenser 104 connected between the two terminals 30 and 31 of discriminator 16, a suitable battery or other bias source 105 being interposed in the circuit of grid 101.

In operation, and momentarily assuming zero output from discriminator 16, tube 98 and resistor 94 are so selected and arranged that the potential of lead 30 provides a desired normal bias voltage for tube 86. This bias is just beyond cut-off, so that adjustment of tap 85 will permit tube 86 to conduct only during less than one-half cycle of source 32. By properly setting tap 85, the oscillator frequency may be adjusted to its normal value, or be manually tuned. The appearance of a positive or negative discriminator output voltage correspondingly modifies this bias and thereby changes the amplification of tube 86 to vary the energization of the tuning strut and to vary the oscillator frequency to maintain its desired condition.

The present circuit, however, also provides an additional feature which shifts the normal bias

for grid 86 in response to a persisting off-frequency condition of the oscillator 13. Such a persisting off-frequency condition is evidenced by a fixed voltage output from discriminator 16. Such a fixed voltage output will charge up condenser 104 and will thus vary the potential of grid 101. This, in turn, varies the current passing through resistor 94 and correspondingly changes the potential of lead 30 which determines the normal bias for tube 86. Resistor 103 and condenser 104 have a sufficiently long time constant so that tube 98 does not respond to rapid or short changes in discriminator output. In this way a persisting tendency to change frequency is substantially overcome, and the oscillator frequency is maintained more nearly constant at its desired value.

With switch 93 turned to the "off" position, voltage divider 107 energized from source 95 impresses normal bias on tube 86 and thereby provides the same operating condition, but adapted only for manual control by means of tap 85.

Fig. 10 is similar to Fig. 9 and shows only the portion of Fig. 9 within the dotted rectangle 108. In Fig. 10 the bias for the grid 101 of tube 98 is provided by a resistor 109 connected in series with its cathode 97. No by-pass condenser is needed for resistor 109, since tube 98 responds exclusively to unidirectional potentials. Otherwise Fig. 10 is the same as the corresponding part of Fig. 9.

Fig. 11 shows another similar circuit, again being similar to the portion in rectangle 108 of Fig. 9. In Fig. 11, however, the adjustment of the normal bias for tube 86 is provided by selecting resistor 94 and condenser 96 to have a large time constant so that any transient or short-duration signals impressed on grid 101 will be able to change the potential of lead 30 only after condenser 96 has become charged. With a long time constant circuit 94, 96, therefore, the change in the potential of lead 30 will correspond only to persisting signals impressed on grid 101, and the circuit will therefore function in the same manner as the circuits of Figs. 9 and 10.

Fig. 11 also includes a provision for rendering the automatic normal bias adjustment of tube 86 inoperative. For this purpose a voltage divider 111 is connected between source 95 and ground. The tap 112 of voltage divider 111 is chosen to provide a potential equal to the normal bias desired for tube 86. By making the resistance of voltage divider 111 small in comparison to the series circuit composed of resistor 94 and tube 98, and by closing switch 113, the potential of lead 30 is determined almost exclusively by voltage divider 111 and is rendered substantially independent of any control by tube 98. Thus, upon closing switch 113, the effect of tube 98 is almost eliminated, and the circuit will operate in a fashion similar to that of Fig. 8.

It will be apparent that in each of the circuits herein described, the output of the discriminator may also be supplied to a suitable utilization circuit 15 which will thereby respond to a demodulated version of any frequency modulated signal received by antenna 11.

Accordingly, by the present invention I have provided an extremely useful and highly efficient automatic frequency control system particularly adapted to the automatic frequency control of thermally tuned high frequency oscillators.

As many changes could be made in the above construction and many apparently widely different embodiments of this invention could be made without departing from the scope thereof, it is in-

tended that all matter contained in the above description or shown in the accompanying drawings shall be interpreted as illustrative and not in a limiting sense.

5 What is claimed is:

1. Automatic frequency control apparatus, comprising a controlled oscillator having a frequency-determining circuit and thermally-actuated means for tuning said circuit, means for deriving a control signal corresponding to deviation of the output frequency of said oscillator from a desired value, a control tube having an anode, a control grid and cathode, means connecting said signal-deriving means to said control grid to impress said control signal thereon, an output impedance, a source of alternating voltage, means connecting said source between said anode and cathode in series with said output impedance, means for deriving an alternating output voltage from said output impedance, a source of adjustable alternating voltage, means for combining said alternating output voltage in phase opposition with an adjustable alternating voltage derived from said latter source, and means for heating said tuning means by said combined voltages to restore said oscillator frequency to the desired value.

2. The apparatus defined in claim 1, wherein said output impedance is connected in the plate circuit of said control tube.

3. The apparatus defined in claim 1, wherein said output impedance is connected in the cathode circuit of said control tube, said control tube being adapted to operate as a cathode follower.

35 4. Automatic frequency control apparatus for a variable-frequency device having a frequency-determining element and means for tuning said element, said apparatus comprising means for deriving a control signal whose magnitude corresponds to the magnitude of the deviation of the frequency of said device from a desired value and whose polarity corresponds to the sense of said deviation, a multi-element control tube, means connecting said signal-deriving means to one of the elements of said tube, an output impedance, a source of alternating voltage connected to said control tube in series with said output impedance, means for deriving an alternating output voltage from said output impedance, a second source of alternating voltage, means combining said alternating output voltage in phase opposition with an alternating voltage derived from said last-named source, and means for actuating said tuning means in accordance with the resultant of said combined voltages to restore said device frequency to the desired value.

50 5. Automatic frequency control apparatus, comprising a controlled oscillator having a frequency-determining circuit and thermally-operated means for tuning said circuit, means for producing a control signal corresponding to deviation of the output frequency of said oscillator from a desired value, a control tube having a control grid and an anode, means for connecting said signal-deriving means to said control grid to impress said control signal thereon, a source of alternating voltage, means for connecting said source of alternating voltage to said anode, a source of adjustable alternating voltage, means for combining the alternating output voltage of said tube with said adjustable alternating voltage in phase opposition thereto, and means for controlling said thermally-operated tuning means by said combined voltage to maintain said oscillator output frequency at the desired value.

6. Frequency control apparatus, comprising a controlled oscillator, means for producing a signal whose magnitude corresponds to the magnitude of the deviation of the output frequency of said oscillator from a desired value and whose polarity corresponds to the sense of said deviation, a control tube having a control grid and an anode, means for impressing an alternating voltage on said anode, means for controlling said control grid by said signal, means for combining the output of said control tube with a fixed alternating voltage in phase opposition to said first voltage, and means for controlling the frequency of said oscillator by said combined voltages.

7. Frequency control apparatus, comprising a controlled frequency source, means for producing a signal whose magnitude corresponds to the magnitude of the deviation of the output frequency of said source from a desired value and whose polarity corresponds to the sense of said deviation, a variable voltage divider, a source of alternating voltage connected across said divider, means coupled to said signal-producing means and to said divider for controlling the output alternating voltage of said divider by said signal, and means for controlling the frequency of said source by said output alternating voltage.

8. Automatic frequency control apparatus, comprising a controlled oscillator having a thermally - tuned frequency-determining circuit, means for deriving a control signal corresponding to deviation of the output frequency of said oscillator from a desired value, a pair of control devices, each having an anode, cathode and grid, said cathodes being connected together and said grids being connected together, a common resistor means connected to said cathodes, means for connecting said signal-deriving means to said grids to impress said control signal thereon, a source of alternating potential connected to one of said anodes, and means for tuning said circuit in response to the alternating component of the current flowing to said other anode to restore said oscillator frequency to its desired value.

9. Automatic frequency control apparatus, comprising a controlled frequency source having a frequency-determining circuit, means for producing a control signal whose magnitude corresponds to the magnitude of the deviations of the output frequency of said source from a desired value and whose polarity corresponds to the sense of said deviation, means responsive to said control signal for deriving an alternating voltage corresponding to said signal, means for amplifying said alternating voltage, means for controlling said amplifying means in response to said control signal, and means responsive to said amplified voltage for tuning said circuit to restore said source frequency to and maintain it at said desired value.

10. A frequency control apparatus, comprising a controlled oscillator having a thermally-tuned frequency-determining circuit, a source of adjustable alternating potential, means for controlling said circuit by said potential whereby the output frequency of said oscillator may be adjusted to a desired value by adjustment of said potential, an amplifier device connected between said source and said circuit, means for modifying the amplification of said device in accordance with the deviation of said output frequency from said desired value to restore said oscillator frequency to its desired value, and means responsive to persisting frequency deviations of said

oscillator frequency for modifying said adjusted potential.

11. Apparatus as in claim 10, wherein said last-named means comprises an electron discharge device whose conductance is delayedly controlled in response to said deviations.

12. Frequency control apparatus, comprising a controlled oscillator having an adjustable frequency-determining circuit, a source of adjustable alternating potential, means for adjusting the frequency of said circuit in response to said potential, said adjusting means comprising a variable amplification device having a normal amplification, means responsive to frequency deviation of said controlled oscillator frequency from a desired value for modifying the amplification of said device with respect to said normal amplification so as to restore said oscillator frequency to its desired value, and further means responsive to persisting oscillator frequency deviations for modifying said normal amplification.

13. Automatic frequency control apparatus, comprising a controlled oscillator having an adjustable frequency-determining circuit, a source of adjustable alternating potential, means for adjusting the frequency of said circuit in response to said potential, said adjusting means comprising an amplifier having variable amplification and a normal bias, means for producing a control signal responsive to frequency deviation of said controlled oscillator frequency from a desired value, means for superposing said signal upon the normal bias of said amplifier to modify the amplification thereof so as to restore said oscillator frequency to its desired value, and further means responsive to persisting oscillator frequency deviations for modifying said normal bias.

14. Frequency control apparatus, comprising a controlled oscillator having an adjustable frequency-determining circuit, means for adjusting the frequency of said circuit and comprising a variable amplification device having a normal amplification, means responsive to frequency deviation of said controlled oscillator from a desired value for modifying the amplification of the device to restore said oscillator frequency to its desired value, and further means responsive to persisting oscillator frequency deviations for modifying said normal amplification.

15. Frequency control apparatus, comprising a controlled frequency source having an adjustable frequency-determining circuit, means for adjusting the frequency of said circuit in response to frequency deviation of said controlled source frequency from a desired value, said adjusting means including an amplifier having a variable amplification and a normal bias, and means responsive to persisting source frequency deviations for modifying said normal bias.

16. Frequency control apparatus, comprising a controlled frequency source having an adjustable frequency-determining circuit, means responsive to deviation of said controlled source frequency from a desired value for restoring said source frequency to its desired value, and further means responsive to persisting source frequency deviations for modifying the control action of said restoring means whereby said source may be kept in closer correspondence to its desired value.

17. Frequency control apparatus for a variable-frequency device comprising means for producing a signal whose magnitude corresponds to the

magnitude of the deviation of the frequency of said device from a desired value and whose polarity corresponds to the sense of said deviation, variable voltage-dividing means, a source of alternating voltage connected across said voltage-dividing means, means coupled to said signal-producing means and to said voltage-dividing means for controlling the alternating voltage output of said voltage-dividing means in response to said signal, and means for controlling the frequency of said device by said alternating voltage output.

18. Frequency controlling apparatus for a high frequency device having an adjustable frequency-determining element, said apparatus comprising means for adjusting the frequency of said element in response to frequency deviation of said device from a desired value, said adjusting means including an amplifier having a variable amplification and a normal bias, and means responsive to persisting device-frequency deviations for modifying said normal bias.

19. Frequency control apparatus for a high frequency device having an adjustable frequency-

10 determining element, comprising means responsive to deviation of said device-frequency from a desired value for restoring said device-frequency to its desired value, and further means responsive to persisting device-frequency deviations for modifying the action of said restoring means whereby said device-frequency may be kept in close correspondence to its desired value.

Certificate of Correction

Patent No. 2,454,265.

November 16, 1948.

EDWIN T. JAYNES

It is hereby certified that errors appear in the printed specification of the above numbered patent requiring correction as follows:

Column 6, line 23, for the word "distributor" read *discriminator*; column 10, line 62, claim 5, for "ouput" read *output*; and that the said Letters Patent should be read with these corrections therein that the same may conform to the record of the case in the Patent Office.

Signed and sealed this 14th day of June, A. D. 1949.
